SHOE CONSTRUCTION

William B. Stroup, Indianapolis, Ind.

Application October 14, 1949, Serial No. 121,372

3 Claims. (Cl. 36—8.5)

1

This invention relates to a novel shoe construction, and more particularly to a shoe construction having heel, shank and toe sets for reinforcing the shoe in a manner to properly support a foot in its natural position, thus providing for greater wearing ease, better foot support and longer life of shoes.

It is an object of this invention to provide a shoe of the kind to be more particularly described hereinafter having heel, shank and toe sets particularly formed and positioned in a shoe to support the foot in its natural position. A shoe last is formed for properly receiving the sets in their respective positions in the shoe and for forming a depression in the sole of the shoe for properly receiving the great toe of the foot in its naturally-depressed relation to the other toes.

Another object of this invention is to provide a shoe construction and last having a depressed great toe portion in which the great toe may be depressed in its natural position, a heel set in the shoe to make the counter and heel position permanent during the wearing life of the shoe, and a shank set to support the shank position and arch structure while the shoe is being worn.

Still another object of this invention is to provide a heel set for a shoe construction of this kind which is supported in the counter to hold the heel against sliding in the shoe and wearing the counter into a distorted side bearing position. By supporting the foot against sliding in the heel of the shoe, the foot will constantly be supported on its upper flat position during the life of the shoe construction.

A further object of this invention is to provide a shoe-supporting member for engagement in a shoe, the arch-supporting member being fixed at one end and slidably engaging in a shank set carried by the insole to provide for the free movement or flexing of the shoe having the built-in support while still providing for the firm support of the arch of the foot when totally supported on the sole of the shoe.

With the above and other objects in view, my invention consists in the arrangement, combination and details of construction disclosed in the drawings and specification, and then more particularly pointed out in the appended claims.

In the drawings:

Figure 1 is a perspective view of a shoe last and related shoe insole constructed according to an embodiment of my invention;

Figure 2 is a bottom plan view of the shoe last;

Figure 3 is a bottom plan view of the shoe insole having heel and toe sets and a shank support constructed according to this invention;

Figure 4 is a longitudinal section of a shoe of this invention applied on a related shoe last, the last being partly broken away and partly in section;

2

Figure 5 is a transverse section taken on the line 5—5 of Figure 4;

Figure 6 is a fragmentary detailed section taken on the line 6—6 of Figure 4;

Figure 7 is a transverse section of the heel set removed from the shoe construction;

Figure 8 is a plan view of the toe set blank removed from the shoe;

Figure 9 is a plan view of the shank set before engagement in the shoe.

Referring to the drawings, the numeral 10 designates generally a shoe constructed according to an embodiment of my invention. The shoe 10 is particularly designed for containing within the sole 11 a toe set 12, a heel set 14 and a shank or arch-supporting member 15. The counter 16 is of a substantially conventional construction secured to the side edges or periphery of the welt-type sole. In accordance with the general welt-type shoe construction, a resilient inner lining or pad 17 is disposed between the inner sole 18 and outer sole 19 along the toe and shank portions of the shoe.

From a consideration of the relative positions of the toes of a human foot when standing on a soft surface, as the earth, it will be noted that the great toe is depressed further than the other toes and portions of the foot. This is the natural position of the toes, heel and ball of the foot, and if the foot may be supported in a shoe in the same manner, it can be readily seen that added foot comfort and greater shoe life will be provided. With this in mind, it is proposed that in this shoe 10, the inner sole 18 shall be formed with a depression 20 in place to receive the great toe below the plane of the lower surface of the other toes and the heel of the foot. Also, the toe set 12 will be supported in the toe portion of the shoe to provide a reinforcement in the shoe adjacent the great toe depression 20 to support the other toes at a slightly higher level.

The toe set 12 is formed of a suitable rigid material, as stainless steel, aluminum or other suitable material resistant to rust and corrosion.

45 The set 12 will be formed of a flat blank 24 formed of a pair of arcuately bowed oval sections 25 and 26 having an outwardly-extending arm 27 extending from one side of one of the oval sections, as the section 26, clearly shown in Figure 8

50 of the drawings. The oval sections will be bent to a face to face abutting position with the arm 27 extending outwardly perpendicular to the section 26, then reverted for underlying the lower edges of the upstanding oval sections. The underlying arm 27 constitutes a base member for attachment to the lower side of the inner sole 18, while the bowed, arcuate, oval sections will define an upwardly-extending set member 28 engageable through an opening 29 in the toe portion of the inner sole 18. The set member 28 will be

positioned on the inner side of the great toe recess or depression 20 on the inner side of the great toe and will protrude slightly upwardly above the upper surface of the insole to form a sort of bearing member to hold the toe portion of a foot from sliding transversely of the toe portion of the shoe 10. Suitable nails, not shown in the drawings, or other suitable fastening means are used for securing the base member 27 to the insole.

The last 30, on which the shoe 10 is formed, is provided with a set member 31 on the lower side of the great toe position for forming the depression 20 in the insole. A notch or opening 32 is formed in the last 30, adjacent the toe set member 31 for receiving the toe set member 28 in the formation of the shoe. A suitable anvil or abutment plate 34 is secured on the last 30 adjacent the opening 32 for forming an abutment to bend the nails engaged through the insole 18 for securing the toe set 12 thereto.

The heel set 14 is secured in the heel portion of the shoe 10 for supporting the heel of a foot against sliding in the shoe and distorting the counter 16 in the manner resulting from walking in shoes of a conventional construction. The heel set 14 is formed of a plate of metal 35 bent into a forwardly-opening U-shape, similar to the configuration of the lower portion of the heel of the shoe 10. The plate 35 is disposed within the heel of the shoe within the counter and is formed with an inturned marginal flange 36 on the lower edge thereof for engagement under the heel portion of the insole 18, clearly noted in Figure 3 of the drawings.

A pair of inwardly-extending tabs or arms 37 are formed on the opposite ends of the flange 36 to be secured by conventional fastening means to the lower side of the insole 18 for securing the heel set thereon. The flange 36 and tabs 37 are disposed between the insole and heel H of the shoe 10.

An abutment plate or anvil 38 is secured on the heel portion of the last 30 for providing an abutment to be engaged by the nails used for securing the heel set 14 to the shoe 10 in the construction thereof.

The arch support 15 is formed with an elongated bar 39 formed of metal or other suitably rigid material having a degree of resiliency for bending when a force is applied to the ends thereof. The bar 39 is fixedly secured to the under side of the insole 18 adjacent the heel H and extends forwardly under the area of the shank portion of the insole 18. The forward, lower end of the arch-supporting bar 39 is slidably engaged in a socket member 40 disposed rearwardly of the ball portion of the insole 18 on the lower side, as clearly noted in Figure 4 of the drawings.

The socket member 40 is formed of a metal plate 41 bent upon itself to form a pair of overlying oval plates 42 and 44 secured together along one transverse edge. The overlying plates are bowed along the length thereof and spaced apart along the edge opposite the juncture of the plates to define the socket 40 open on the rear end thereof. A pair of laterally-extending tangs 45 are formed on one edge of one of the plates, as the plate 42, for penetrating engagement into the under side of the insole 18 between the insole 18 and outer sole 19.

The forward end of the supporting bar 39 is slidably engaged in the open end of the socket member 40 to provide for the free sliding move-

ment of the supporting bar 39 upon flexing of the shoe in the region of the arch of the shoe as effected by the normal walking of a person wearing the shoe 10. While the free end of the supporting bar 39 is free to slide between the insole 18 and outer sole 19 when walking in the shoe 10, the bar 39 will provide for the proper and desirable rigid support of the arch of a foot when bearing downwardly on the arch of the shoe 10.

10 The heel plate 38, carried by the shoe last 30, also provides an abutment for the free end of the nail engaged through the rear end of the arch-supporting bar 39 for securing the supporting bar 39 to the insole 18.

15 I do not mean to confine myself to the exact details of construction herein disclosed, but claim all variations falling within the purview of the appended claims.

I claim:

20 1. In a shoe, an inner sole having a toe section, a heel section and a shank section interconnecting said heel and toe sections, there being a longitudinally extending depression provided in said toe section contiguous to one side thereof for the reception of the big toe of a foot, a toe set disposed adjacent to and spaced from the opposite side of said toe section and secured thereto for holding the big toe against displacement transversely of said inner sole, a heel set circumscribed about said heel section and secured thereto, and an arch support fabricated of resilient material disposed longitudinally of and underlying said shank section having the end contiguous to said heel section secured thereto and having the other end thereof mounted for movement longitudinally of said inner sole.

25 2. In a shoe, an inner sole having a toe section, a heel section and a shank section interconnecting said heel and toe sections, there being a longitudinally extending depression provided in said toe section contiguous to one side thereof for the reception of the big toe of a foot, a toe set disposed adjacent to and spaced from the opposite side of said toe section and secured thereto for holding the big toe against displacement transversely of said inner sole, a heel set circumscribed about said heel section and secured thereto, and an arch support fabricated of resilient material disposed longitudinally of and underlying said shank section having the end contiguous to said heel section secured thereto and having the other end thereof mounted for movement longitudinally of said inner sole.

30 30 3. In a shoe, an inner sole having a toe section, a heel section, and a shank section interconnecting said heel and toe sections, there being a longitudinally extending depression provided in said toe section contiguous to one side thereof for the reception of the big toe of a foot, a toe set disposed adjacent to and spaced from the opposite side of said toe section and secured thereto for holding the big toe against displacement transversely of said inner sole, a heel set circumscribed about said heel section and secured thereto, a longitudinally disposed socket member positioned beneath said inner sole and having its open end facing toward said heel section, and an arch support fabricated of resilient material disposed longitudinally of and underlying said shank section having the end contiguous to said heel section secured thereto and having the other end

35 45 55 65 70 75 85 95

thereof extending into the open end of said socket member and slidably received and supported therein for movement longitudinally of said inner sole.

WILLIAM B. STROUP.
